J. C. HARTMAN

LINOLEUM CUTTER

Filed August 15, 1922

Patented June 15, 1926.

1,589,156

UNITED STATES PATENT OFFICE.

JOHN C. HARTMAN, OF LANCASTER, PENNSYLVANIA, ASSIGNOR TO ARMSTRONG CORK COMPANY, OF LANCASTER, PENNSYLVANIA, A CORPORATION OF PENNSYLVANIA.

LINOLEUM CUTTER.

Application filed August 15, 1922. Serial No. 582,050.

The present invention relates specifically to cutters particularly adapted for the cutting of linoleum and similar materials.

At the present time it is customary in the art to which the present invention relates to cut or trim the edges of linoleum by the use of a knife having a curved cutting blade, the blade being pulled across and through the material to be cut. A knife of this character has not been altogether satisfactory for the reason that it is comparatively difficult to produce a straight edge therewith and for the further reason that considerable difficulty is frequently experienced in cutting heavy linoleum.

It has also been proposed to provide cutters comprising a blade adapted to be pushed through the linoleum, the linoleum being raised into position to be cut by strips of metal engaging the floor and underrunning the linoleum. Cutters of this type, while satisfactory for certain purposes, are comparatively difficult to operate and are not provided with means for guiding the same.

By the present invention there is provided a linoleum cutter adapted to be easily and efficiently operated and provided with means whereby straight cut edges are insured.

In the accompanying drawings there is illustrated a preferred embodiment of the present invention, it being understood that the drawings do not define the limits of the invention and that changes may be made in the construction and operation disclosed without departing from the spirit of the invention or scope of my broader claims.

In the drawings,

Figure 1 is a perspective view of a cutter constructed in accordance with the present invention;

Figure 2 is a side elevation of the construction illustrated in Figure 1;

Figure 3 is an end view of the construction illustrated in Figures 1 and 2, the knife being removed therefrom, and

Figure 4 is a sectional view on the line IV-IV of Figure 2.

In accordance with the present invention, a preferred form of linoleum cutter may comprise a blade carrying member 2, which may conveniently be in the form of a casting of suitable shape, having an operating handle 3 by which the same may be pushed forwardly during the cutting operation. The member 2 may also be provided with a sup-

plemental knob or handle 4 to which may be secured a pull cord 5 which may be used by a helper to assist in the cutting operation.

The blade carrying member is preferably provided with a lower substantially flat 60 linoleum engaging face 6 and with a depending rib or head 7 projecting therebelow and constituting a guiding means. In the cutting operation it is customary to overlap the respective edges E and E' which are to be 65 cut, as clearly shown in Figure 1, and then move the cutter thereacross. It will be apparent that the guide rib 7 will effectively guide the cutter to form straight cut edges which will accurately register when the cut-away portions are removed.

The member 2 may conveniently be formed with a kerf 8 extending throughout a portion of the length and width thereof and opening through the lower face 6. This kerf is adapted to receive a blade 9 of a standard linoleum cutter of any usual construction. The blade may conveniently be held in the desired position to insure the projection of the requisite amount of the cutting point by providing an adjusting screw 10 adapted to engage the back edge of the blade and a clamping screw 11 adapted to engage one side of the blade and clamp the same against one side of the kerf.

As there are several different sizes and shapes of linoleum cutting knives, I have found it desirable to provide a series of tapped openings 12 into any one of which the clamping screw 11 may be inserted. This 80 makes the blade carrying member useful with a large variety of knives and insures flexibility of adjustment.

Certain advantages of the present invention arise from the provision of a linoleum 95 cutter adapted to utilize standard linoleum knives.

Other advantages of the invention arise from the provision of a linoleum cutter having means for effectively guiding the same 100 during the cutting operation.

I claim:

1. In a linoleum cutter, an elongated blade carrying member having a blade receiving opening extending lengthwise thereof, spaced handles on said member, means for clamping the blade in position in said opening, and guiding means on said member adapted to engage the linoleum to be cut, substantially as described.

2. In a linoleum cutter, a blade receiving member having a kerf formed therein and intersecting the lower face and one end thereof only, and means for clamping a blade in position in said kerf, substantially as described.
3. In a linoleum cutter, a blade carrying member having a blade receiving opening therein so dimensioned as to substantially shield all but the desired cutting portion of a blade, a blade for said member, means for clamping the blade in position in said opening, means engaging a back edge of the blade for adjusting the position of the blade in the opening, and a projecting handle on said blade to facilitate positioning thereof, substantially as described.
4. In a linoleum cutter, a blade receiving member having a kerf formed therein and intersecting the lower face thereof, means operable in one direction for clamping a blade in position in said kerf, and means operable at substantially right angles to said first mentioned means for adjusting the position of the blade in said kerf, substantially as described.
5. In a linoleum cutter, a blade carrying member having a linoleum engaging face provided with a projecting guide rib, there being a blade receiving opening intersecting said face, a blade in said opening having a horizontally extending handle portion and a vertically extending cutting portion and means for clamping the blade in position in said opening, substantially as described.
6. In a linoleum cutter, a blade carrier having a longitudinally extending kerf adapted to receive and support the blade of a standard linoleum knife, and means for maintaining a standard linoleum knife in operative position in said kerf, substantially as described.
7. In a linoleum cutter, a blade carrier, an operating handle projecting therefrom, and means for clamping a standard linoleum knife in operative relation to said carrier, substantially as described.
8. In a linoleum cutter, a blade carrier of generally elongated form having a longitudinally extending kerf formed therein and intersecting the bottom face and one end of the carrier only, a linoleum knife having its blade inserted within said kerf and having its handle portion substantially in longitudinal alignment with the carrier, and means for clamping said blade in position in the kerf, substantially as described.
9. In a linoleum cutter, a blade carrier of generally elongated form having a longitudinally extending kerf formed therein and intersecting the bottom face and one end of the carrier only, a linoleum knife having its blade inserted within said kerf and having its handle portion substantially in longitudinal alignment with said carrier, and means for clamping said blade in position in the kerf, said carrier having guiding means projecting therefrom adjacent one side of and substantially parallel to the kerf for engaging one edge of the material being cut, substantially as described.
10. In a linoleum cutter, a blade carrier of generally elongated form having a longitudinally extending kerf formed therein and intersecting the bottom face and one end of the carrier only, a linoleum knife having its blade inserted within said kerf and having its handle portion substantially in longitudinal alignment with the carrier, and means for clamping said blade in position in the kerf, said carrier having a pair of operating handles formed thereon, one of said handles being adjacent each end of the carrier, substantially as described.
11. In a linoleum cutter, a blade carrier of generally elongated form having a longitudinally extending kerf formed therein and intersecting the bottom face and one end of the carrier only, a linoleum knife having its blade inserted within said kerf and having its handle portion substantially in longitudinal alignment with the carrier, means for clamping said blade in position in the kerf, and other means operable in the plane of the kerf for adjusting the position of said blade, substantially as described.
12. In a linoleum cutter, a blade receiving member having a blade receiving opening therein, a blade having a projecting handle, means for holding said blade in position in said opening with said handle projecting into operative position, and a projecting shoulder on said member adapted to engage one edge of the material being cut for guiding the movement of the cutter during the cutting operation, substantially as described.

In testimony whereof I have hereunto set my hand.

JOHN C. HARTMAN.
